UNITED STATES PATENT OFFICE.

ROBERT L. TUTTLE, OF ST. CHARLES, MISSOURI, ASSIGNOR OF ONE-HALF TO FRANK G. CULLOM, OF ST. CHARLES, MISSOURI.

MIRROR.

1,250,723.

Specification of Letters Patent. Patented Dec. 18, 1917.

Application filed June 1, 1917. Serial No. 172,248.

To all whom it may concern:

Be it known that I, ROBERT L. TUTTLE, a citizen of the United States, residing at St. Charles, in the county of St. Charles and 5 State of Missouri, have invented a new and useful Mirror, of which the following is a specification.

It is the object of the present invention to provide a novel means whereby a mirror 10 may be held in vertically adjusted positions, the mirror being tilttable with respect to a vertical plane.

With the above and other objects in view which will appear as the description proceeds, the invention resides in the combination and arrangement of parts and in the details of construction hereinafter described and claimed, it being understood that changes in the precise embodiment of 20 the invention herein disclosed can be made within the scope of what is claimed, without departing from the spirit of the invention.

In the accompanying drawings:

25 Figure 1 shows in elevation, a device constructed in accordance with the present invention;

Fig. 2 is a vertical sectional detail showing the means whereby the mirror is immediately supported for vertical sliding movement;

Fig. 3 is a section taken approximately on the line 3—3 of Fig. 2;

Fig. 4 is a section taken approximately on the line 4—4 of Fig. 2; and

Fig. 5 is a fragmental side elevation showing a portion of the rider and the spring which is assembled therewith.

In carrying out the present invention 40 there is provided a base 1 which may include a platform 2 and legs 3. Fixed to and upstanding from the platform 2 is a standard 4 which may be surmounted by a cap 5. The standard 4 is of tubular form and is 45 provided with a rectangular bore 6, and with a longitudinal slot 7 opening into the bore 6, the slot 7 preferably being coextensive in length with the standard 4.

A rider 8, preferably taking the form of 50 a block, is mounted to reciprocate vertically in the bore 6 but is held against rotation therein. The rider 8 is provided in one side with recesses 9 across which extend shafts 10, wheels 11 being journaled on the shafts

10. In its opposite side, the rider 8 is supplied with a longitudinal recess 14. Mounted in the recess 14 is a spring strip 15, held to the rider 8 by securing elements 16. The spring strip 15 terminates in a curved head 17 bearing against one side of the bore 6 of the standard 4, the wheels 11 bearing against the opposite side of the bore of the standard, and the recess 14 being enlarged laterally at one end as shown at 18, to facilitate the resilient action of the head 17 of the 65 spring 15. Ordinarily, the spring 15 70 stands from the rider 8, as shown in Fig. 5, but when the rider is in the bore 6 of the standard 4, then the spring 15 is compressed as shown in Fig. 4. It will be obvious from the foregoing that the spring 75 constitutes a means whereby the rider 8 may be held in vertically adjusted positions in the bore 6 of the standard 4, the wheels 11 facilitating a vertical adjustment of the 80 rider.

An arm 20 is inserted at one end into the rider 8 intermediate the ends of the rider, and is held in place by a securing element 21. The arm 20 slides in the slot 7 of the 85 standard 4 and terminates in an enlarged head 22 through which is passed a shaft 23. By means of clips 24, the ends of the shaft 23 are attached to the rear side of a mirror 25.

The clips 24 hold the shaft 23 frictionally against the rear side of the mirror 25, and consequently, the mirror 25 will remain in the positions to which it may have been swung, in the direction of the arrows A of 90 Fig. 2. By means of the arm 20, the rider 8, and the mirror 25, may be raised and lowered, the wheels 11 facilitating a raising and lowering of the rider, and the spring strip 15 serving to hold the rider in any 95 position to which it may have been adjusted vertically, within the rectangular bore 6 of the standard 4.

Having thus described the invention, what is claimed is:

In a device of the class described, a tubular standard provided with a bore and having a longitudinal slot communicating with the bore; means for holding the standard in an upright position; a rider mounted to reciprocate in the bore; a wheel carried by one side of the rider and coacting with one wall of the bore; a spring carried by the 100 105

other side of the rider and coacting with the opposite wall of the bore to hold the rider in adjusted positions longitudinally of the standard; an arm carried by the rider and 5 projecting outwardly through the slot; and a mirror assembled with the arm.

In testimony that I claim the foregoing

as my own, I have hereto affixed my signature in the presence of two witnesses.

ROBERT L. TUTTLE.
